No. 36,814.

Patented February 23, 1904.

UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A CANDELABRUM.

SPECIFICATION forming part of Design No. 36,814, dated February 23, 1904.

Application filed January 12, 1904. Serial No. 188,799. Term of patent 7 years.

To all whom it may concern:

Be it known that I, ALBERT STEFFIN, a citizen of the United States, residing at the city of New Bedford, in the county of Bristol and 5 State of Massachusetts, have invented a new, original, and ornamental Design for Candelabra, of which the following is a specification, reference being had to the accompanying drawing, forming part thereof.

o The figure is an elevational perspective of a candelabrum, showing my new design.

What I claim as new, and desire to secure by Letters Patent, is—

The ornamental design for candelabra, as herein shown.

ALBERT STEFFIN.
